UNITED STATES PATENT OFFICE

107,590

DESIGN FOR A THEATER LOBBY ADVERTISING DEVICE

Arthur A. Young and Arthur R. Telser, Chicago, Ill.

Application February 13, 1937, Serial No. 67,655

Term of patent 14 years

To all whom it may concern:

Be it known that we, Arthur A. Young and Arthur R. Telser, both citizens of the United States, residing at Chicago, in the county of Cook and State of Illinois, have invented a new, original, and ornamental Design for a Theater Lobby Advertising Device, of which the following is a specification, reference being had to the accompanying drawing, forming a part thereof:

lobby advertising device showing our new design, and

Figure 2 is a side elevational view of the design shown in Figure 1.

We claim:

The ornamental design for a theater lobby advertising device as shown.

ARTHUR A. YOUNG.

ARTHUR R. TELSER.
